UNITED STATES PATENT OFFICE.

HENRY T. JULIUS FUHRMAN, OF BROOKLYN, NEW YORK.

CASKET.

Application filed December 5, 1923. Serial No. 673,579.

To all whom it may concern:

Be it known that I, HENRY T. JULIUS FUHRMAN, a citizen of the United States, residing at Brooklyn, in the county of 5 Kings and State of New York, have invented certain new and useful Improvements in Caskets, of which the following is a specification.

The main object of this invention is to 10 provide a burial casket constructed in such manner as to retard disintegration of the corpse contained therein for a greater length of time than is possible with the present type of caskets.

Another object is to provide a burial casket composed of a material impervious to 15 water or moisture and constructed as a body and a cover, these members hermetically sealing the interior when closed so that no 20 vermin or air may gain access thereto.

These and other objects will become apparent in the description below in which characters of reference refer to like-named parts in the drawing.

Referring briefly to the drawing, Figure 25 1 is a front elevational view of the burial casket closed.

Figure 2 is a sectional elevational view of the same.

Figure 3 is an enlarged sectional elevational view of a corner of the casket showing the means employed for hermetically sealing the same.

Referring in detail to the drawing, the 35 numeral 1 indicates the base of the casket and constitutes a separate member which may be fitted to the casket at will. The faces of the base may be curved or ornamented into any shape desired.

The body of the casket comprises a rectangular bottom 2 from the edges of which 40 rise end walls 3 and side walls 4. The walls and the bottom are of moderate thickness, and are slightly greater in cross section than the prevailing type. The entire body is cast of a compound consisting of infusorial earth (diatomite) and magnesite or other material. These elements when 45 properly mixed have the quality of being lighter than wood and imperviousness to both air and water. In casting the body of diatomite and magnesite, the entire surfaces

become glazed upon hardening. This glazed 55 finish may be made to imitate wood or various other materials. Each of the walls 3 and 4 has a semicircular groove 5 which ex-

tends parallel to the length of the walls. The groove of one wall communicating with the grooves in the adjacent walls. The corners of the body are prevented from being 60 chipped or otherwise damaged by the guard strips 6. The side walls 4 have plate brackets 7 mounted thereon near their opposite ends from which lugs project, said lugs being used to pivotally support carrying handles 8.

A cover comprising a top 9 and walls 10, and side walls 11, is hingedly secured to one of the side walls 4 of the body and is also constructed of the same material as the 70 body, its longitudinal dimensions being also similar to the body. The external corners are protected by strips 12 and the parallel edges are similarly protected by strips 13. The entire inner surface of the cover has a 75 fabric covering concealing its surfaces. This covering indicated by the numeral 14 is generally of silk cloth and is ruffled or formed into folds. The interior surfaces of the walls of the body are similarly covered 80 by a fabric 15. The edges of the cover are provided with semicircular inverted grooves, the latter aligning with the grooves 5 when the cover is closed down on the body. The 85 grooves 5 have a flexible rubber tubing fixed therein, said tubing being adapted to be inflated by an air pump thru a valve 18. The edges of the body and cover normally do not contact with each other but are slightly spaced-apart by a crevice 20. The 90 entire crevice is concealed from view by the strips 19 which extend around the casket body and are secured thereto.

When the corpse has been deposited in the body the cover is closed down upon the 95 latter after the tubing 17 has been inflated. The cover is then locked to the body, the locking means not being shown on the drawing. The body and cover being composed of diatomite and magnesite will prevent the entrance of moisture or vermin, and the inflated tubing between the body and the cover will prevent the moisture and 100 vermin from entering the casket thru the crevice. In this manner premature disintegration of the corpse is prevented.

I claim:

1. In a burial casket, a box-like body composed of a mixture of diatomite and magnesite, the walls and bottom being integral, 110 the walls of the body having a continuous and endless semicircular groove, the walls

2
of the cover having an inverted semicircular groove which aligns with the groove in the body, a flexible endless tubing mounted in the groove of the body, a valve on said tubing adapted to be used when inflating the same, and strips covering the crevice between the body and cover when the latter is in closed position.

5 2. A burial casket, a box-like body composed of diatomite and magnesite, the walls and bottom being integral, a cover on said

body, strips secured to the edges of the sides of said cover, a tubing resting on the edge surfaces of the sides and end walls of said body, grooves on said walls receiving said tubing, a valve for inflating said tubing and grooves on the cover, said cover being adapted to rest on said tubing above the body to hermetically seal the chamber in the body. 15

In testimony whereof I affix my signature.

H. T. JULIUS FUEHRMAN.
